UNITED STATES PATENT OFFICE.

AMANDUS C. ROESSLER, OF LAKWOOD, OHIO, ASSIGNOR TO THE ROTARY MACHINE & ENGINEERING COMPANY, OF CLEVELAND, OHIO, A CORPORATION OF OHIO.

ROTARY PUMP.

Original applications filed February 10, 1923, Serial No. 618,173, and August 19, 1926, Serial No. 130,185. Divided and this application filed April 2, 1927. Serial No. 180,554.

This invention relates to new and useful improvements in pumps and more particularly to the type of pump comprising a casing having an approximately cylindrical chamber, a rotor or piston cylinder mounted in said casing and in close contact with a portion of the wall of said chamber and a sliding blade carried by said rotor.

The object of this invention is to provide a rotary pump which shall be smooth in action and practically free from pulsations.

Another object is to provide a rotary pump which shall be reversible in action and which can be fabricated in a practical manner without the use of packing and packing glands.

Another object of my invention is to provide such a construction in a pump of the type set forth as will eliminate the back pressure in the pump which retards the operation and causes hammering and undue vibration.

Another object of my invention is to provide a pump which can be cheaply produced, which will be durable in operation and very efficient.

Another object of my invention is the provision of new and improved means for packing the end of the piston blade.

A further object of my invention is to provide such an arrangement of parts as will effectually prevent the fluid, which is being pumped, from being compressed while passing through the pump chamber.

With these objects in view and with the intention of securing other advantages which will hereinafter appear, my invention consists in certain novel features of construction and combination of parts described in the specification, particularly pointed out in the claims and illustrated in the accompanying drawings.

Referring to the accompanying drawings Fig. 1 is a central vertical sectional view of a pump embodying my invention; Fig. 2 is a section on line 2—2, Fig. 1; Fig. 3 is a vertical sectional view similar to Fig. 1 and showing a slight modification; Fig. 4 is an enlarged sectional view of one end of the blade; Fig. 5 is a side view of the blade part-

ly in section and showing the rocker at the end of the blade in elevation; and Fig. 6 is a diagrammatic view illustrating the generation of the curve of the bore of the cylinder.

Again referring to the drawings 3 represents the casing of the pump which is in the form of a cylinder and is mounted on an integrally formed base 4. At each end of the cylinder is formed an annular flange 5. The end plates or cylinder heads are shown at 6 and 7 and these plates are secured to the cylinder or casing by means of bolts 9 which screw into the flanges 5 on the casing. On the outer face of each of the cylinder heads is formed a series of radially disposed webs 65 or fins, shown at 11 and 12. These webs both reinforce the heads and also serve to radiate the heat generated through the operation of the pump and keep the pump in a sufficiently cool condition to prevent the "freezing" of 70 the movable parts.

On the inner face of each head or end plate is formed a seat shown at 13 and 14, and at the center of each seat is formed a bearing, indicated at 15 and 16. The bearing 15 is preferably closed at its outer end, as at 17, thereby eliminating the necessity of 75 packing said bearing.

The pump chamber is shown at 19 but the bore is not truly cylindrical, the dotted lines 80 indicating the true circle and the full lines the actual curvature of the bore. The line 2—2 (which may be termed the median line) divides the pump chamber into substantially symmetrical halves and the points where this 85 line cuts the top and bottom of the pump chamber are concentric, that is to say, they are equal distances from the point where the line X—X intersects the line 2—2 and as before stated the dotted line indicates the circle described from this point whereas the actual bore is slightly different upon each side of the median line 2—2. In this pump chamber thus bored I employ a rotating blade 90 more fully described hereinafter and it is essential that this blade should contact at all times at both of its ends with the walls of the cylinder and as the blade which I propose to use is fixed in its length it is obvious that 95 this blade constitutes a movable chord and 100

as the rotor which carries this blade is mounted eccentrically with reference to the cylinder the proper curvature of the bore can be mathematically obtained from the eccentric relation of the rotor to the bore and the length of the chord. This curve is known as a limaçon curve and in Fig. 6 I have shown one manner of generating the curve of the bore 19 as is known in the art.

- 10 The rotor or piston carrying member 20 is, in general, cylindrical in form and is of such length that it extends from side to side of the chamber and the ends thereof fit snugly in the seats 13 and 14 in the cylinder heads. The rotor is provided at one end with a stud shaft 21 which extends into the blind bearing 15 and at its other end with a driving shaft 22 which extends through the bearing 16 and may be provided with a drum 15 or other means, not shown, for driving the rotor. The general arrangement of the rotor with respect to the case is such that the rotor is in close contact with a portion of the wall at the top of the chamber at all times.
- 20 In the rotor is formed a slot 25 which passes through the axis of the rotor and the length of said slot corresponds to the length of the pump chamber. In the slot 25 is slidably mounted a blade 26 the width of which is approximately equal to the length of the pump chamber and the length of said blade is such that both ends of said blade are always in contact with the walls of said chamber. The blade is preferably made of steel 30 and in the end of each blade is formed a semi-circular or concave seat 27. In each seat 27 is arranged a strip of packing material 28. In forming this packing strip I take a rod of packing material which is circular in cross-section and having the same radius as the arc of the seat in the end of the blade. I then cut away a portion at one side of the rod above the center line thereof and then impart a curvature to the face, thus 35 formed on the rod, corresponding to the general or average curvature of the wall of the pump chamber. This strip is then set into the seat in the end of the blade so that the base or portion of the strip opposite the truncated face fits into said seat and the side portions project beyond the seat and the face thereof abuts against the wall of the chamber. It will readily be seen that owing to this construction the strip is free to rock in 40 its seat as the blade revolves so that the face of the packing strip will at all times conform and press tightly against the wall of the pump chamber. Furthermore as the packing rocks one way or the other it will automatically increase or decrease the length 45 of the blade and will therefore provide for the ever changing radius of curvature of the wall of the chamber or any probable imperfection therein and will compensate the wear 50 on the wall of the chamber. Also as said

packing strip has a definite side area projecting beyond the end of the blade, it will follow that when the fluid is being forced through the pump the pressure of the fluid will act against the side of the packing strip and cramp the strip against its seat greatly increasing the efficiency of the packing.

The intake port 30 is preferably formed at the top of the intake side of the chamber and the outlet port 31 is arranged on the opposite side of the chamber. The relative arrangement of the two ports is such that as one end of the piston blade passes the intake port the other end of the blade will be starting to travel across the outlet port and therefore the outlet port is opened for the escape of fluid back of the forward end of the blade as soon as the rearward end of the blade begins to act on said fluid. Consequently no compression can take place within the pump chamber. Also during a portion of the rotation of the rotor both ends of the piston blades act at the same time to expel the contents of the pump directly through the outlet port, because the forward end of the blade will be forcing fluid through the outlet port all the time it is passing across the outlet port and the rearward end of the blade will at the same time be forcing fluid through the outlet port back of the forward end of the blade.

As before mentioned the arrangement is such that a portion of the surface of the rotor for the full length of the rotor is always in gas or liquid tight contact with a portion of the wall of the chamber. It therefore follows that as soon as the forward end of the blade passes or clears the outlet port a closed pocket is formed ahead of the blade. When the pump is in operation this pocket will be filled with gas or liquid and the only chance for it to escape is between the end of the blade and the wall of the chamber. This pocketing of the gas or liquid causes a continual pounding of the pump and ultimately results in loosening the pump from its mounting and injury to the driving mechanism. To obviate this difficulty I form an open duct or groove 35 in the top wall of the pump chamber at the outlet side of said chamber. This groove extends longitudinally of the chamber and in close proximity to the line of contact between the rotor and the wall of the chamber. A subsidiary outlet or vent passageway 36 is formed in the wall of the pump chamber and one end of this passageway communicates with the duct 35 and the other end communicates with the outlet passage from the outlet port 31. The fluid which would otherwise be trapped finds a ready means of escape by the way of the duct 35 and the vent passageway 36, making possible a perfect delivery of the whole contents of the pump. Also all extra strain placed upon the pump on account of the

pocketing of the fluid is entirely eliminated together with the hammering caused thereby, rendering the operation of the pump noiseless and greatly increasing the durability of the pump.

In the form of the invention illustrated in Fig. 3 I employ a pump body or casing A, the bore A' of which is constructed in substantially the same manner as the bore of the cylinder of the form shown in Figs. 1 and 2, that is to say, the bore of the cylinder is constructed upon a limaçon curve and the details of the generation of this curve will be more fully described hereinafter. This casing has its ends closed by means of plates securely bolted to the casing, and formed with bearings for the rotor D, the rotor being cylindrical in shape similar to that illustrated in Figs. 1 and 2.

The intake or suction opening F is located at one end of the casing and the outlet or discharge opening G is preferably arranged diametrically opposite the opening F. The opening F communicates with the passage F' and the inlet or suction port F² cut in the wall of the cylinder establishes communication between the inlet or suction passage in the bore of the pump. The rotor D has a slot or opening H cut therein for the blade I. At each end of the blade is mounted a rocker K which contacts with the curved surface of the pump cylinder or bore. The ends of the blade are grooved and provided with an undercut J and in these grooves are mounted the rockers K which are free to oscillate as the rotor revolves. This oscillation is produced by the pressure of the fluid against the front face of the rocker and/or by the outer ends of the rocker making a contact with the pump bore during rotation and it will be seen that unless the friction or contact surface between the blade and rockers is less than that between the rocker and bore free oscillation will be prevented holding the rockers rigid in which case they would bind against the bore and prevent rotation of the rotor and for that reason the grooves are undercut so that there is less surface of the rocker in contact with the end of the blade than with the bore of the cylinder.

The ports are located in such a manner that the inlet port is closed before the outlet port opens, the outlet port being indicated at G and in this manner all back pressure from the suction is prevented and likewise compression of the fluid in the pump chamber. A certain amount of lead may be given so that the blade travels, say the width of the rocker after closing the suction port and before reaching the discharge port. In this case the discharge port must open at the moment that the distance between the bore and rotor at the lower edge of the rocker is the same as at the other end of the blade that is between the bore at the suction side and the

rotor. If this relationship is not maintained hammering will occur with considerable vibrations.

The ends of the blades being provided with rockers in undercut grooves the friction between the rocker and blade is reduced to a point below the friction between the rocker ends and bore and consequently these rocker ends will always turn sufficiently to maintain a working contact between the blades and the bore and inasmuch as the blades with rockers attached thereto are of constant length and as the bore is constructed upon the limaçon curve previously referred to there will be the proper working contact during the entire movement of the blades and irrespective of the direction of rotation.

In Fig. 6 I have illustrated a diagram for the generation of the curve which is as follows: 40, 40 and 41, 41 indicate two lines crossing each other at right angles at the point 42 and from this point 42 is described a circle 43. Through the line 40, 40 is drawn line 44, 44 parallel with the line 41 and the distance between the lines 41 and 44 is the amount of eccentricity existing between the rotor and the bore of the casing. On the line 40, 40 midway between the lines 41 and 44 there is described a circle 45 which circle is divided into a sufficient number of points 46 and from the point 47 there are drawn lines 48 from the point 47 through the various points 46 and on these lines 48 there are marked off points 49, these being measured from the point 46 and the distances from the points 46 to the points 49 are all equal to the radius of the circle 43. A line drawn through the various points 49 will give the correct limaçon curve which is the curvature of the bore of the cylinder and as the rotor turns within the cylinder driving the blades, the movement of the blades back and forth through the slots will cause the central point of each blade to describe a circle similar to 45 and in this manner the blades will be held in constant contact with the walls of the pump cylinder due to the fact that their lengths are fixed and the curvature of the bore is upon the curve indicated. From the above it will be noted that the bore of the pump is not in the form of a true circle at any point or for any sensible arc whatever. At each end of the opening H in the rotor, the surface is cut back as shown at X in Fig. 3. These cut backs flatten the rotor at the points where they are located, thus allowing foreign matter to pass over the top from the discharge to suction side of the pump when the blade is in the position where the rotor makes contact with the bore.

In rotary pumps as heretofore constructed the difficulties in operation have resulted from imperfections in manufacture and imperfections or errors of design. In order to compensate for errors in manufacture the

provision of rollers at the ends of the blades has been sufficient but such rollers or other appliances are not sufficient to provide for the combined errors of manufacture and the departure from theoretically correct designs. For this reason centrifugal force, springs and flexible devices have been employed for the purpose of securing blade contact with the pump barrel. By constructing the bore 10 upon the limaçon curve as hereinbefore set forth, it is possible to dispense with various forms of flexible devices and employ a blade of fixed dimensions having roller contacts with the bore of the pump and which will 15 effectively prevent pounding and slippage.

This application is a division of my pending applications, Serial No. 618,173, filed February 10, 1923, and Serial No. 130,185, filed August 19, 1926, and the subject-matter thereof not described and claimed herein 20 is reserved for said applications.

What I claim is:

1. A rotary fluid pressure machine comprising a casing having inlet and outlet 25 ports and a chamber in communication with said ports, the peripheral wall of said chamber conforming to a limaçon curve, a rotor mounted eccentrically within said chamber, a rigid blade member reciprocable diamet- 30 rically in said rotor, and movable non-yielding packing means mounted in the opposite ends of the blade and adapted to make a sealing contact with the wall of said chamber in all positions of said blade.

2. A rotary fluid pressure machine comprising a casing having inlet and outlet ports and a chamber in communication with said ports, the peripheral wall of said chamber conforming to a limaçon curve, a rotor 40 mounted eccentrically within said chamber, a rigid blade member reciprocable diamet- rically in said rotor, and rigid packing means rockably mounted in the opposite ends of the blade and adapted to make a sealing contact with the wall of said chamber in all positions of said blade.

3. A rotary fluid pressure machine comprising a casing having inlet and outlet ports and a chamber in communication with 50 said ports, the peripheral wall of said chamber conforming to a limaçon curve, a rotor mounted eccentrically within said chamber, a rigid blade member reciprocable diamet- rically in said rotor, and pivoted packing 55 means mounted in the opposite ends of the blade and held in place by the chamber wall, said packing being adapted to contact with the wall of the chamber in advance of the median plane of the blade.

4. A rotary fluid pressure machine comprising a casing having inlet and outlet ports and a chamber in communication with said ports, the peripheral wall of said chamber conforming to a limaçon curve, a rotor 60 mounted eccentrically within said chamber,

a rigid blade member reciprocable diamet- rically in said rotor, and pivoted packing means mounted in the opposite ends of the blade and having a chamber contacting face curved to conform approximately to the curvature of the cylinder wall. 70

5. A rotary pump comprising a casing, a rotor eccentrically mounted in said casing, and a blade carried by the rotor and sliding therethrough and including pivoted pack- 75 ing means at the extremities thereof, the casing being bored on a limaçon curve, generated by a chord, whose length is equal to the length of the blade on its medial line, and whose movement is such that its center de- 80 scribes a circle whose diameter is equal to the amount of eccentricity of the rotor with reference to the casing along the medial line, and whereby the pivoted ends of the blade make contact with the bore of the casing at 85 all points of rotation.

6. A rotary fluid pressure device comprising a chamber shaped to conform to a lima- 90çon curve and having a rotor eccentrically mounted for rotation therein and inlet and outlet ports spaced apart angularly on the side of the chamber toward which the rotor is mounted, a blade extending through the rotor and provided with seats at its ends, rockers mounted in said seats for movement 95 toward either side of the blade, said rockers having working faces adapted to contact with the wall of the chamber at their leading edge whereby pressure from fluid being pumped is exerted on the forward edge of the rockers to maintain said leading edge in close contact therewith. 100

7. A rotary fluid pressure device comprising a chamber having closed ends and a peripheral wall shaped to conform to a limaçon curve, a rotor mounted therein with its axis of rotation passing through the chordal center of said limaçon and parallel to the principal axis of the chamber, a blade extending through the rotor transversely of its axis, 110 said blade being shorter than the chordal length of said limaçon and provided with seats at its extremities, and rockers mounted in said seats for pivotal movement toward either side of said blade, said rockers having 115 working faces conforming to the interior of said chamber adapted to bear against it in either direction of rotation.

8. A rotary fluid pressure device comprising a chamber the peripheral wall of which is shaped to conform to a limaçon curve, a rotor eccentrically mounted in said chamber in fluid tight contact with the wall of said chamber and parallel to the principal axis of said chamber, a blade carried by said rotor and 120 slideable therethrough and including movable packing means journaled in the extremities thereof, inlet and outlet ports communicating with said chamber on opposite sides of 125 said rotor, said outlet port including a por- 130

tion in the chamber wall terminating in close proximity to the line of contact between the rotor and bore and so arranged as to avoid the trapping of incompressible fluid in the chamber and consequent hammering.

9. A rotary fluid pressure machine comprising a casing having inlet and outlet ports and a chamber in communication with said ports, the peripheral wall of said chamber conforming to a limaçon curve, a rotor mounted eccentrically within said chamber a rigid blade member reciprocable diametrically in said rotor, and movable non-yielding packing means mounted in the opposite ends of the blade and adapted to make a sealing contact with the wall of said chamber in all positions of said blade, the mounting of said packing means being such as to reduce the frictional contact between said packing means and blade member.

10. A rotary fluid pressure device comprising a chamber shaped to conform to a limaçon curve and having a rotor eccentrically mounted for rotation therein, and inlet and outlet ports spaced apart angularly on the side of the chamber toward which the rotor is mounted, a blade extending through the rotor and provided with seats at its ends, rockers mounted in said seats for movement toward either side of the blade, said rockers having working faces adapted to contact with the wall of the chamber at their leading edge whereby pressure from fluid being pumped is exerted on the forward edge of the rockers to maintain said leading edge in close contact therewith, said outlet port including a portion in the chamber wall terminating in close proximity to the line of contact between the rotor and bore of the chamber for the purpose of increasing the capacity of the pump and prevent hammering.

11. The combination with a pump chamber, the bore of which is a limaçon curve generated on a circle, the diameter of which is equal to one-half the difference between the diameter of the rotor and the diameter of the pump chamber on the median line, of a rotor mounted eccentrically to the pump chamber, a slidably mounted blade in the rotor, oscillating rockers mounted in the ends of the blade the ends of the blade being cut away to provide seats for the rockers and the rocker being so shaped that pressure from the fluid being pumped is exerted upon the forward edge of said rocker, said blade sliding through the center of rotation, inlet and outlet ports arranged so that the inlet port is closed substantially at or slightly before the outlet port opens, to avoid compressing the fluid within the casing or the production of pressure before the outlet port opens.

12. The combination with a pump chamber, the bore of which is a limaçon curve generated on a circle the diameter of which is equal to one-half the difference between the diameter of the rotor and the pump chamber on the median line, of a rotor mounted eccentrically to the pump chamber, a slidably mounted blade in the rotor, oscillating rockers mounted in the ends of the blade, said blade sliding through the center of rotation, inlet and outlet ports so arranged that the inlet port is closed substantially at or slightly before the outlet port opens, thereby avoiding compressing the fluid within the pump chamber, or the production of pressure before the outlet port opens.

In testimony whereof, I have signed my name to this specification.

AMANDUS C. ROESSLER.
